WINDOW CLEANING DEVICE
Maury W. Wayne, 13454 McCormick St.,
Van Nuys, Calif.
Filed Aug. 22, 1963, Ser. No. 303,756
5 Claims. (Cl. 15—322)

This invention relates to apparatus for cleaning surfaces such as windows and more particularly to improvements therein.

A considerable amount of effort has been directed to making apparatus for cleaning windows, and more particularly for cleaning car windows. Although a large number of mechanical devices have been tried, none of these apparently has been successful as witnessed by the fact that car windows are still cleaned in the average service station by first wetting with any suitable cleaning solution and then wiping dry with a rag or toweling.

The reason why devices made heretofore have not been successful especially in the case of car windshields, is that, the windows are left streaked and/or wet after their use and thus effectively are not accomplishing very much in the way of really cleaning a window.

An object of this invention is the provision of a device for cleaning windows which does not leave a streaked or wet window.

Another object of the present invention is to provide a device for rapidly cleaning windows so that they are left clean.

Yet another object of the present invention is the provision of a novel, unique and effective window cleaning device.

These and other objects of the invention may be achieved in apparatus which includes a window cleaning head having an operative face made of a suitable rubber-like material. The face has spaced parallel scrubbing teeth defining passageways therebetween which extend from either side of a central opening in said face. On either side of the scrubbing teeth are squeegee members. The squeegee members also define channels therebetween which however, are open to permit communication with the central hole in the operating face. A vacuum or low pressure air source communicates with this central hole. On either side of the operating face are pressure operated valves which communicate through the head to a source of water. When the operating face is brought against a window or other surface to be cleaned, the pressure valves are pushed in sufficiently to enable the water to flow onto the window. The motion of the head against the window brings into the play the scrubbing teeth which loosens dirt particles. These dirt particles are flushed by the water being sucked through the passageways formed by the teeth into the central hole which has the vacuum source applied thereto. A manually operated water cutoff control is also provided in the operating head which is closed when the window has been cleaned of dirt to permit the squeegee to literally sweep any water which remains on the surface being cleaned toward the central opening wherein the water is drawn in as a result of the vacuum being applied thereto. The end of the operation leaves a window which not only is clean but is also dry.

The novel features that are considered characteristic of this invention are set forth with particularity in the appended claims. The invention itself, both as to its organization and method of operation, as well as additional objects and advantages thereof, will best be understood from the following description when read in connection with the accompanying drawings, in which:

FIGURE 1 is a front view of an embodiment of this invention;

FIGURE 2 is a side view and section of the embodiment

2

ment of the invention taken along the lines 2—2 of FIGURE 1;

FIGURE 3 is a plan view and section taken along the lines 3—3 of FIGURE 1;

5 FIGURES 4 and 5 show how the front face of the embodiment of the invention can adapt itself to conform to clean curved surfaces.

Reference will now be made to the drawings and more specifically to FIGURE 1 which comprises a front view of the invention, FIGURE 2 comprises a view in section along the lines 2—2 of FIGURE 1, and FIGURE 3 which comprises a view in section along the lines 3—3 of FIGURE 1. This invention comprises a housing 10, made of any suitable rigid material, having a handle portion 10A adapted for being held in the hand, and a head portion 10B. The head portion effectively has a rectangular shape and is supported at its center from the handle portion. A cleaning member 12 is mounted on the front side of the head member 10B. It is made of a material such as rubber or neoprene. The front face of the cleaning member 12 comprises two double squeegee members 16, 18, which define the upper and lower ends of the front face of the cleaning member. In between the squeegee members are several scrubbing teeth 20.

25 As shown in FIGURE 1 the scrubbing teeth comprise spaced parallel ridges which extend from a center hole almost to the outside ends of the cleaning member 12. Effectively these scrubbing teeth define channels which lead to a hole 22 positioned in the center of the cleaning member 12. The two double squeegee members 16, 18 each comprises an outer squeegee respectively 17, 19 which extend the length of the head member, and an inner squeegee respectively 17a, 17b, 17c and 19a, 19b, 19c. Each inner squeegee comprises a short center portion, respectively 17b, 19b, with two long portions respectively 17a, 17c, and 19a, 19c, positioned spaced on either side of the short portions. The spacing between the short and long portions of the respective inner squeegee 17, 19 are situated where required in order to provide 40 a path to the central hole 22.

Extending from these double squeegee members 16, 18 are two side flange members 24, 26. These side flange members extend back from the squeegees over an edge of the head member 10B, and are clamped thereon by 45 means of plates respectively 28, 30. Plates 28, 30, are attached to the body of the head member 10B by a plurality of screws respectively 32, 34.

Positioned at the front face of the cleaning member and on either side of the scrubbing teeth 20, are pressure operated valves respectively 36, 38. These pressure operated valves are fitted into the ends of the respective passageways 40, 42, which are moulded in the rubber of the cleaning member 12. These passageways communicate with passage extension members 44, 46, 55 also made of rubber, which in turn fit into passageways 48, 50, which are formed in the head portion 10B. The passages 48, 50, communicate with a vertical passage 52 which extends through the hand holding portion 10A and is coupled in turn to a pipe 54 which is connected 60 to a water source, not shown. A manually operated valve member 56, which is controlled by a knob 58 can be used to prevent water which is received through the pipe 54 flowing out of the openings in which the pressure valve members 36, 38 are inserted even though these pressure valves are pushed back to open positions.

The central opening 22 in the front face of the cleaning member communicates through a tube 60 which extends from this opening back into a receiving opening 62 in the head member 10B. This receiving opening 70 communicates with a vertical opening 64 which extends through the handle portion 10A to a pipe 66. This pipe

leads to a vacuum source not shown, for applying suction thereto.

The operation of the device is rather unique and achieves results which have not been achieved heretofore, namely that the window on which it is used is left both clean and dry. When the cleaning member 12 is brought against a window the pressure operated valves 36, 38, are moved into the passages 40, 42, thus opening the passages so that water fed therethrough from the water source through the pipe 54 is directed against the window and spreads over the surface thereof. Reciprocal vertical motion over the surface of the window while pressing against it causes the scrubbing teeth 20 to loosen any dirt, or film on the window. Since the pressure valves 36, 38, are maintained open while this is occurring, water is continually flowing. By reason of the vacuum applied through the pipe 66 to the opening 22, the scrubbing teeth 20, and the window surface provide flow channels or tunnels extending to the opening 22, and the water carrying the dirt is literally sucked through these flow channels into the opening 22. The double squeegee members 16, 18 serve to dry the surface of the window and any water which the double squeegee members 16, 18 collect in the course of their operation is likewise guided or drawn into the opening 22.

In order to completely dry the window the knob 53 is depressed, thus cutting off the supply of water to the passages 40, 42. The double squeegee members 16, 18 together with the vacuum being applied to the opening 22, then serve to completely dry the window surface.

Because the cleaning head of the invention is made of a resilient material, and because of the manner of supporting the cleaning head by resilient structures as shown in FIGURES 2 and 3, the head will conform to a convex window surface 70, as shown in FIGURE 4, or to a concave window surface 72, as shown in FIGURE 5. This is important, since in cleaning the windshield of the modern automobile for example, unless the cleaning device can be used with curved window surfaces, it has little utility in cleaning the modern automobile windshield.

This invention by reason of presenting a cleaning surface which comprises scrubbing teeth which define them a channel leading to a central source of a vacuum, and further by providing a water flow which is channeled toward said vacuum, not only thereby providing a mechanism whereby the most stubborn dirt may be scrubbed from the surface of a window, but also enable the loose dirt to be flushed away. Because of the presence of the vacuum substantially all of the water which is emitted from the passages 40, 42, is sucked through the passageways into the vacuum. The cutting off of further water by the manipulating of the knob 53 enables any drops of water which may not have been guided into the vacuum to be collected using the double squeegee members 16, 18 and thereby remove it by the vacuum. In the event of an automobile windshield which has been wetted from other sources, such as rain or fog, then the knob 53 can be manipulated initially to enable the window to be cleaned and dried using the water which is already there.

There has accordingly been described and shown herein a novel, useful and unique cleaning device which can clean and dry windows, and especially the windshields of automobiles.

I claim:

1. A cleaning device comprising handle means for supporting a cleaning member, said cleaning member having a cleaning face, said cleaning face having a first opening through the center thereof, passage means for coupling a vacuum source through said handle means to said opening in the center of said cleaning face, a second and third opening respectively on either side of said central opening and spaced therefrom, normally closed pressure operated valve means in each of said second and third openings responsive to pressure of said valve means against a work surface to move to an open posi-

tion, passage means for communicating between a source of water and said respective second and third openings whereby when said pressure operated valves are opened water flows from said second and third openings, a plurality of passageways extending between said second and third openings and said central opening, said plurality of passageways being defined by parallel spaced resilient scrubbing teeth, and a first and second squeegee member positioned on either side of said central opening and said second and third openings and extending across said cleaning face.

2. A cleaning device comprising a cleaning member made of a resilient material, said cleaning member having a substantially elongated shape, said cleaning member having a cleaning surface, a first opening centrally located in said cleaning surface and extending through said cleaning member, second and third openings disposed on either side of said centrally located opening and spaced therefrom, said second and third openings each having therein a normally closed pressure operated valve means responsive to pressure of said valve means against a work surface to move to an open position, means for applying suction through said cleaning member to said central opening, passage means for applying water through said cleaning member to said second and third openings, a plurality of scrubbing teeth disposed on said cleaning surface, said scrubbing teeth extending between said central aperture and said second and third apertures to define multiple passageways extending between said apertures, a first and second squeegee spaced on either side of said three apertures and extending across said cleaning member, and further valve means for closing off said passage means to said second and third apertures.

3. A windshield cleaning device comprising a cleaning member, a support member, means attaching said cleaning member to said support member, said cleaning member being made of resilient material, and having a substantially rectangular shape, first, second and third apertures in said cleaning member, said first aperture being centrally disposed in the operating face of said cleaning member, said second and third apertures being disposed near the outside edges of said cleaning member aligned with an on either side of said first aperture, normally closed pressure valve operated means in each of said second and third openings responsive to pressure of said valve means against a work surface to move to an open position, a plurality of spaced scrubbing teeth formed of said resilient material and extending between said first and third apertures and said first and second apertures to thereby define a plurality of passageways therebetween, a squeegee member positioned on both sides of said first, second and third apertures and extending across said cleaning member, passage means extending from said first opening through said cleaning member and said support member for affording communication between a vacuum source and said first opening, and water passage means extending through said cleaning member and said support member for enabling the application of water to said pressure operated valve in said second and third openings.

4. Apparatus for cleaning and drying the surface of a window comprising a resilient cleaning head having a cleaning surface thereon, said cleaning surface having a first and second squeegee formed on opposite edges thereof, a plurality of spaced resilient scrubbing teeth on said cleaning face and extending between said first and second squeegees along said cleaning face and parallel to said first and second squeegee, a central opening extending from said cleaning face through said cleaning member, said central opening communicating with all the spaces between said scrubbing teeth, two side openings respectively positioned near the outside edges of said cleaning face on either side of said central opening and between said first and second squeegees, normally closed pressure operated valve means in each of the two side

openings responsive to pressure on a face thereof against a work surface to move to an open position, passage means for applying suction to said central opening, further passage means for applying water to said two side openings, and further valve means which is manually operable to open or close said passage means for applying water to said two side openings.

5. Apparatus for cleaning the surface of a windshield comprising a resilient cleaning member having a cleaning face, a first and second opening, said first opening being adjacent one edge of said cleaning face, said second opening being adjacent an edge opposite to said one edge of said cleaning face, said first and second openings each having therein normally closed pressure operated valve means for applying water to said first and second openings through said cleaning head when opened responsive to pressure on said valve means by a work face, a central opening extending through said cleaning face and said cleaning head, means for applying suction to said central opening through said cleaning head, means establishing passageways between said first and second openings and said central opening comprising a plurality of resilient scrubbing teeth spaced from one another and extending between said central opening and said first and

second openings, and a first and second double squeegee member respectively positioned on either side of said three openings and extending across said cleaning face, the innermost of each of said first and second double, squeegee members being interrupted to afford communication of passages in said double squeegee with said central opening.
